CLAIM

The ornamental design for boot flip flop, as shown and described.

DESCRIPTION

FIG. 1 is a perspective view of a boot flip flop according to the present application.

FIG. 2 is a front view of the boot flip flop of FIG. 1.

FIG. 3 is a back view of the boot flip flop of FIG. 1.

FIG. 4 is a left view of the boot flip flop of FIG. 1.

FIG. 5 is a right view of the boot flip flop of FIG. 1.

FIG. 6 is a top view of the boot flip flop of FIG. 1; and,

FIG. 7 is a bottom view of the boot flip flop of FIG. 1.

The broken lines are included for the purpose of illustrating environmental structure and form no part of the claimed design.
